UNITED STATES PATENT OFFICE

GREGORY H. LIFUR, OF LOS ANGELES, CALIFORNIA

COOLING TOWER

Application filed August 1, 1927. Serial No. 209,751.

My invention relates to a liquid cooling tower particularly designed to utilize natural air circulation as the cooling medium.

An object of the invention is to provide in 5 a tower of the character described, an improved circulation of air therethrough by means utilizing a novel disposition of louver boards.

Another object of the invention is to provide 10 a supporting means for the louvers and which also functions as a bracing means for the tower.

A further object of the invention is to provide 15 in a tower of the character described, means independent of the louvers for preventing the loss of fluid from the tower when under excessive air circulation conditions.

Other and ancillary objects of my invention will be suggested in the following description and in the use of the device of my invention. Certain of the objects, or certain 20 portions or combinations of the objects of my invention may be attained with the use of less than all its advantageous features, or 25 with modifications within its purview. It is petitioned therefore, that my invention be limited only by the claims constituting its final determination.

In the accompanying drawings forming 30 part of this specification:

Figure 1 is a plan of a cooling tower embodying my invention.

Fig. 2 is a transverse sectional view taken 35 on the line 2—2 in Figure 1.

Figure 3 is an enlarged fragmentary plan of the forward right-hand corner of Fig. 1.

Fig. 4 is an elevation of the corner of Fig. 3; and

Fig. 5 is an enlarged fragmentary trans- 40 verse sectional view taken on the line 5—5 in Fig. 1.

As herewith particularly illustrated, the features of my invention are incorporated in a cooling tower 6 having a frame formed 45 with a requisite number of upright posts 7 and carrying a series of superimposed decks 8. The decks 8, it will be noted are fixedly related to the posts and are perforated to permit the distributed escape of intercepted liquid therethrough. As here shown, the

decks comprise deck joists 9 fixed to opposed posts 7 and have slats 11 fixed thereacross in spaced relation.

Since the tower is particularly intended to be disposed for the natural circulation of air 55 therethrough, louvers are provided, such louvers functioning the most advantageously direct the air stream through the falling liquid and particularly at the surface of the decks as well as to prevent the blowing of the 60 liquid from the tower. Support for the necessary louvers is provided by means of bracket members 12, such members preferably extending upwardly and outwardly from joists 65 of the decks inwardly of their edges to and beyond an adjacent post and being fixed to the deck and post as by bolts 13 and 14 respectively, whereby the protruding portion 15 of the member 12 constitutes a cantilever 70 bracket arm for the support of a louver. Since 75 a triangle is defined by and between the inner portion of member 12, the post, and the deck, it will be obvious that each member 12 also functions to stiffen and brace the frame by 80 maintaining the angular relation of the post 75 to the deck. Members 12 are provided to extend from each of the decks at the different edges thereof; a set of as many members 12 is provided for each deck as there are posts 85 7. Also, the members 12 are of like length 80 and are similarly disposed whereby those at a given side of a deck may cooperate to define a plane of support for a louver.

Louver boards 16 are mounted on and between the arms 15 at each edge of the deck, 85 such boards extending outwardly from the posts whereby relatively large openings are defined between the lower edges 17 of the boards and the deck level. The louver boards 90 associated with each set of members 12, it 95 will be noted, are coterminous to provide a continuous louver about the tower for each deck 8, whereby superimposed sets of louver boards are provided, the corresponding louver boards of the different sets being parallelly related. Preferably, the louver boards 16 are imperforate and extend upwardly at least to the level of deck above that from which the members 12 which support them 100 extend. As here shown, the upper edges 18 of

the louver boards of a set lie substantially as far above a given deck as their lower edges 17 lie below it, it being noted that the edges 17 lie closest to the upper deck of an adjacent pair. In this manner, the horizontal plane of the upper edges 18 of a set of louver boards is below that of the lower edges 17 of the set immediately above it.

The hereinbefore described disposal of the louvers with respect to the decks is somewhat different from that heretofore commonly used, and possesses a number of marked advantages thereover. Briefly, the usual practice has heretofore been to extend the louvers directly from the surface of each deck so that a deck and its louvers together defined a saucer-like depression, whereby the major circulation of air laterally between decks of a tower so constructed, takes place adjacent the lower surface of the deck above, and little if any air is enabled to sweep across the top surface of the lower deck, whereby the liquid retarded thereat is not subjected to the cooling effect of air as much as the liquid falling from the deck above. By means of the present arrangement in my invention however, a strong and direct air current is assured along the top surface of each deck, whereby a maximum cooling of the liquid is effected. Furthermore, the arrangement now disclosed, by reason of the vertical as well as horizontal spacing of edges 17 and 18 of adjacent louvers provides greater effective air inlet and exit passages to the tower than is permitted with other and prior structures, whereby circulation of the air through the tower is facilitated and the cooling of the liquid is thus still further aided, yet no greater loss of liquid occurs through the blowing of the liquid from the tower on account of the peculiar disposal of the louvers. To further assist in insuring a cooling of the liquid, secondary decks 21 may also be utilized. As here shown, the decks 21 are formed generally similarly to the decks 8 and are suspended from the latter decks as by bolts 22. Preferably, the bolts 22 have long threaded ends for adjustable useful length, and the decks 21 are disposed in the upper portions of the direct air streams across the decks 8 whereby they also receive the full benefit of such streams. Generally, the decks 21 would be suspended in parallel relation to the decks 8, but when a strong wind prevails, they are preferably tilted into the wind whereby they may assist in preventing the blowing of the liquid across and from the decks and so conserve the liquid. Furthermore, to prevent the drops of liquid from falling directly through several decks, the slats 23 of the decks 21 may be disposed in staggered relation to the slats 11 of the decks 8, Fig. 5, when the decks 21 and 8 are parallelly related. In this manner, the cooling of the liquid is further facilitated whereby

towers of less height may be utilized to effect a desired cooling of liquid. As here shown, adjustment of the decks 21 is arranged to be facilitated by the use of wing nuts 24 on the bolts 22, it being obvious that other means of adjustment might be used without departing from the spirit of my invention. It will be noted that the suspended or floating decks 21 may be tilted in many directions, provision having been made to accomplish this by the large clearance holes 25 and 26 of the decks 8 and 21 respectively, Fig. 5.

From the foregoing description taken in connection with the accompanying drawings, the advantages of the construction and method of operation will be readily understood by those skilled in the art to which the invention appertains, and while I have described the principle of operation, together with the device which I now consider to be the best embodiment thereof, I desire to have it understood that the device shown is merely illustrative and that such changes may be made, when desired, as fall within the scope of the appended claims.

Having thus described my invention, I claim as new and desire to secure by Letters Patent of the United States, the following:

1. In a cooling tower of the class described, superimposed perforated decks, and inclined louver boards disposed in similar relation to successive decks, each of said boards having the lower edge thereof disposed above the plane of the lower deck of an adjacent pair and the upper edge thereof disposed above the plane of the upper deck of said pair whereby a planar sweep of air is provided for beneath a said louver board and across the upper surface of a said lower deck.

2. In a cooling tower of the class described, superimposed perforated decks, and superimposed inclined louver boards similarly related to successive decks and having the lower edge of each board disposed above the level of its deck and above the level of the top edge of the immediately underlying board whereby a planar sweep of air is permitted completely across the tower and over the upper surfaces of said decks.

3. In a cooling tower of the class described, superimposed perforated decks of like structure, and inclined imperforate louver boards for and similarly related to said decks and having the lower edges thereof disposed above the planes of their decks whereby to provide for a planar sweep of air through the tower and over the upper surface of the said decks.

4. A cooling tower comprising a supporting structure, a plurality of superposed decks arranged in spaced relation to each other, inclined louvers disposed around said decks and being positioned so that their lower edges will occur substantially midway between two decks and that they will be intersected by the

horizontal plane of a deck substantially mid-way of their height.

5. In a cooling tower of the class described, a plurality of supporting posts at edge points thereof, a perforated deck supported by said posts, and a louver supporting bracket comprising an upwardly and outwardly inclined member having its inner end fixed to said deck within the operative area thereof and to a said post to define a triangle with said deck and post and providing an outwardly protruding arm arranged to function as a cantilever support for the louver.

10 6. In a cooling tower of the class described, a plurality of supporting posts, a deck supported by and between said posts, a bracket comprising a member extending obliquely upwardly from an interior point of said deck to and beyond a post and fixed to said deck and post, and a louver board carried by the portion of said member outwardly of said post.

15 7. In a cooling tower of the class described, a plurality of upright supporting posts, a series of superimposed perforated decks carried directly by said posts, and a secondary perforated deck suspended between a pair of said first-decks in intermediate relation thereto, said secondary deck being supported from the directly superimposed deck and having the perforations thereof in staggered relation to the perforations of said pair of decks.

20 8. In a cooling tower of the class described, a plurality of upright supporting posts, a series of superimposed perforated decks carried directly by said posts, and a secondary perforated deck adjustably suspended between a pair of said first decks.

25 9. In a cooling tower of the class described, a plurality of upright supporting posts, a series of superimposed perforated decks carried directly by said posts, a secondary deck interposed between a pair of said first decks, and means adjustably supporting said secondary deck from the upper deck of said pair whereby both the angular and spaced relation of said secondary deck to the decks of said pair may be varied.

30 10. In a cooling tower of the class described, a plurality of upright supporting posts, a pair of cooling decks carried by and between said posts, and a secondary cooling deck supported intermediate said first decks for angular adjustment with respect thereto.

35 11. In an atmospheric cooling tower having an interior cooling chamber through which fluid is adapted to fall and through which air currents are adapted to pass substantially horizontally, wind directing means at the side of said chamber, and a baffle disposed within said chamber in the path of such currents and spaced from said wind directing means, and adapted to be inclined with respect to the horizontal.

12. In an atmospheric cooling tower having an interior cooling chamber through which fluid is adapted to fall and through which air currents are adapted to pass substantially horizontally, wind directing means at the side of said chamber, a baffle disposed within said chamber in the path of such currents and of said falling fluid, said baffle being spaced from said wind directing means and adapted to be inclined with respect to the horizontal.

70 13. In an atmospheric cooling tower having an interior cooling chamber through which fluid is adapted to fall and through which air currents are adapted to pass substantially horizontally, wind directing means at the side of said chamber, a baffle disposed centrally within said chamber in the path of such currents and of said falling fluid and adapted to be inclined with respect to the horizontal.

80 14. In an atmospheric cooling tower having an interior cooling chamber through which fluid is adapted to fall and through which air currents are adapted to pass substantially horizontally, wind directing means at the side of said chamber, a baffle disposed within said chamber in the path of such currents and adapted to be inclined with respect to the horizontal, and a movable mounting for the baffle whereby it is movable to vary its angle of inclination.

90 15. In an atmospheric cooling tower having an interior cooling chamber through which fluid is adapted to fall and through which air currents are adapted to pass substantially horizontally, wind directing means at the side of said chamber, a baffle disposed within said chamber in the path of such currents and adapted to be inclined with respect to the horizontal, a movable mounting for the baffle whereby it is movable to vary its angle of inclination, and means for so moving the baffle.

100 16. In an atmospheric cooling tower having a vertically arranged series of cooling chambers, a given chamber being vertically defined by spaced upper and lower decks through which fluid is adapted to fall and thus pass substantially vertically through the chamber, wind directing means at the side of said chamber, and a baffle adapted to be inclined with respect to the horizontal and arranged in said chamber in the path of such currents.

110 17. In an atmospheric cooling tower having a vertically arranged series of cooling chambers, a given chamber being vertically defined by spaced upper and lower decks through which fluid is adapted to fall and thus pass substantially vertically through the chamber, a louver for directing air currents through said chamber, and an apertured baffle adapted to be inclined with re-

spect to the horizontal and arranged in said chamber in the path of such currents.

18. In a cooling tower of the class described, a series of relatively fixed and superimposed perforated decks, and a secondary perforated deck adjustably supported between a pair of said first decks for adjustment with respect thereto.

19. In a cooling tower of the class described, a series of relatively fixed and superimposed perforated decks, and a secondary perforated deck adjustably supported between a pair of said first decks for spacing and/or angular adjustment with respect thereto.

In testimony whereof, I affix my signature.

GREGORY H. LIFUR.
